UNITED STATES PATENT OFFICE

130,357

DESIGN FOR A LOUD SPEAKER

Richard A. O'Connor and La Vern Edward Quinnell, Fort Wayne, Ind., assignors to The Magnavox Company, Incorporated, Fort Wayne, Ind., a corporation of Indiana

Application September 12, 1941, Serial No. 103,307

Term of patent 14 years

To all whom it may concern:

Be it known that we, Richard A. O'Connor and La Vern Edward Quinnell, citizens of the United States, residing at Fort Wayne, in the county of Allen and State of Indiana, have invented a new, original, and ornamental Design for a Loud Speaker, of which the following is a specification, reference being had to the accompanying drawing forming a part thereof.

In the drawing:

Fig. 1 is a front elevational view of a loud speaker embodying our novel design;

Fig. 2 is a side elevational view; and

Fig. 3 is a rear elevational view thereof.

We claim:

The ornamental design for a loud speaker, substantially as shown.

RICHARD A. O'CONNOR.
LA VERN EDWARD QUINNELL.
